UNITED STATES PATENT OFFICE.

WILLIAM G. BROWN, OF MONMOUTH, MAINE.

IMPROVEMENT IN SASH-FASTENERS.

Specification forming part of Letters Patent No. 179,155, dated June 27, 1876; application filed June 5, 1876.

To all whom it may concern:

Be it known that I, WILLIAM G. BROWN, of Monmouth, of the county of Kennebec, of the State of Maine, have invented a new and useful Improvement in Sash-Fasteners; and do hereby declare the same to be fully described in the following specification and represented in the accompanying drawings, of which—

Figure 1 is a rear elevation, and Fig. 2 a sectional view, of a window-frame and sashes with my improved sash-fasteners applied thereto. Fig. 3 is a top view, Fig. 4 a horizontal section, and Fig. 5 a transverse section, of the fastener.

In such drawings A denotes the window-frame, and B and C the upper and lower sashes thereof. The sash-fastener is represented as having a bolt-case, a, provided with a bolt, b, upon whose shank is a helical spring, c, for moving said bolt forward. There extends from the bolt a pivot, d, upon which is placed a friction-roller, e. A triangular cam, f, provided with a back stop, g, arranged with it, as shown, bears against the roller, is arranged in the bolt-case in manner as shown, and is fixed to the end of a rod, h, having upon its other end a knob, i. On pressing upon the knob, so as to force the cam f forward into

the bolt-case, the bolt will be crowded back within the case; but on removing the finger from the knob the force of the spring of the bolt will not only advance the bolt, but cause the friction-roller to move the cam backward until the stop g may be in contact with the roller. Each of the sashes is to have a separate fastener, of the kind described, arranged in the window-frame, and with respect to such sash, in manner as represented in Fig. 1, and such sash is to be furnished at its edge, next the fastener, with a series of recesses or holes, k, to receive the bolt, in order for it to hold the sash either closed or more or less open.

A great merit of this sash-fastener is its adaptability to either, and especially to the upper, sash, or capability of being readily applied thereto and to the window-frame.

I claim—

The described improved sash-fastener, consisting of the bolt b, spring c, cam f, stop g, stud or friction-roller e, and the knobbed rod h, all constructed, arranged, and applied to the case a, substantially as set forth.

WM. G. BROWN.
